TUNED COUPLING SYSTEM

Nelson P. Case, Great Neck, N. Y., assignor to
 Hazeltine Corporation, a corporation of Delaware

Application November 25, 1935, Serial No. 51,420

26 Claims. (Cl. 250—20)

This invention relates to tuned coupling systems, and, while it is of general application, it is particularly suitable for use in tunable multi-band radio broadcast receivers.

5 Double-tuned radio-frequency coupling systems are frequently employed in lieu of single-tuned coupling systems in order to utilize the greater selectivity of the double-tuned systems, although their use is frequently attended with problems 10 more difficult of solution than those encountered with single-tuned coupling systems. A characteristic of double-tuned coupling systems is a fairly substantial variation in their gain or transfer ratio for different frequencies within a given 15 band. This characteristic is generally so pronounced that it should not be neglected, particularly inasmuch as it is generally desirable that the gain or transfer ratio of a coupling system be fairly uniform for different frequencies within 20 a given band.

The foregoing characteristic of double-tuned coupling systems gives rise to the problem of procuring a desired slope or variation of the gain or transfer characteristic thereof with frequency. 25 The solution of this problem is complicated by the desirability of maintaining the syntony of the two circuits of a double-tuned coupling system. This complication renders unsatisfactory arrangements which, upon the adjustment of the 30 coupling system to vary the slope of the gain or transfer characteristic, disturb the syntony of the two circuits.

The solution of the above problem is further complicated by practical considerations arising 35 when the coupling system is used for frequencies (such as those above the general broadcast band) for which relatively small inductances are generally provided. Thus in such cases it is difficult to provide and control inductive coupling 40 effects of the relatively small magnitudes involved. When a double-tuned coupling system is variably tuned, it is desirable to tune both the first and second tunable circuits thereof conjointly with each other and with other tunable 45 circuits, by variable condensers having the same minimum and maximum values and the same law of capacitance variation. This renders unsatisfactory arrangements which, upon adjustment of the coupling system to vary the 50 slope of the gain or transfer characteristic, produce misalignment of the first and the second tunable circuits with respect to each other or of either or both of such circuits with respect to any of the other tunable circuits tuned conjointly therewith.

With double-tuned multi-band coupling systems, such as are employed in multi-band radio broadcast receivers, there is the additional problem of providing an arrangement having a gain or transfer ratio which is readily subject to control 5 from band to band. This is desirable in order to compensate for the progressive decrease in the attainable antenna-to-detector over-all gain of multi-band receivers as the bands in which the receiver is operated are higher in the frequency 10 spectrum, so as to obtain an over-all gain which is more nearly uniform from band to band.

It is an object of this invention to provide a double-tuned coupling system in which the gain or transfer characteristic may be given any desired slope without affecting the syntony or alignment of the first and second tuned circuits of the coupling system with respect to each other and/or without substantially affecting the syntony or alignment of either or both of such circuits with respect to related tuned circuits, and in which all the components thereof are such that the design of the system is commercially practical at any portion of the radio-frequency 20 spectrum.

It is another object of the invention to provide a double-tuned coupling system for multi-band radio receivers which is effective automatically to control the over-all gain in accordance with the band in which the receiver is operated, 30 such coupling system being of simple and economical construction and effective without impairment of the selectivity or fidelity of the receiver.

A further object of the invention is the provision of a double-tuned coupling system in which the inductance elements may be constructed and mounted in the receiver with ease and economy.

Other objects of this invention will become apparent from the specification taken in conjunction with the accompanying drawing and appended claims.

The invention contemplates, for a given band of frequencies, a coupling system comprising two tuned circuits having substantially similar reactance characteristics and at least one transfer means between the two circuits having a transfer characteristic variable with frequency and consisting of a self-reactance network all the reactances of which are of the same type and 45 effectively fixed in value, the network having two similar arms of equal effective reactive value individually and symmetrically included in circuit with the tuned circuits, and having another arm 50 symmetrically interconnecting the two similar 55

arms, the control of the transfer action of the transfer means being effected by altering the effective reactive value of the interconnecting arm. Generally, there are two transfer means

- 5 between the two circuits, the two transfer means having transfer characteristics which vary in opposite senses with variations in frequency, so that the resultant transfer characteristic of the two transfer means is substantially uniform over
- 10 a given range of frequencies, or at least is a closer approximation thereto than is obtainable with either transfer means alone. In the preferred arrangement the two transfer means are capacitive in character, the first coupling portions of
- 15 the two circuits of relatively low alternating potential and the second coupling portions of the two circuits of relatively high alternating potential, with no inductive coupling existing between the two circuits. The inductance elements of the
- 20 two circuits may thus be mounted in separate shields. This is of practical advantage in frequency bands in which inductive relationships are difficult to control and thus where individual shields for the several inductance elements are
- 25 of great practical value.

The invention contemplates, for two or more bands of frequencies, a coupling system for each band similar to that described for one band, with the provision that the capacitance of each transfer means is larger as the respective bands are higher in the frequency spectrum.

In the drawing, Fig. 1 is a circuit diagram, partly schematic, illustrating the invention as incorporated in a single band superheterodyne receiver; Fig. 2 is a circuit diagram, partly schematic, illustrating the invention as incorporated in a multi-band superheterodyne receiver, while Fig. 3 is a circuit diagram of a modified form of the coupling system of the receiver of Fig. 2.

40 Referring to Fig. 1, the superheterodyne receiver there shown comprises an antenna circuit 10 connected to a radio-frequency selector and amplifier 11, which may be of conventional type, including a variable tuning condenser 12. 45 The output of selector and amplifier 11 is connected to the input of a variably tuned double-tuned coupling system generally designated 13, the output of which is connected to the input of an oscillator-modulator 14, which may be of conventional type, including a variable tuning condenser 15. In cascade with oscillator-modulator 14 are an intermediate-frequency amplifier 16, a detector and automatic amplification control source 17, an audio-frequency amplifier 18 and a 50 sound reproducer 20. The automatic gain control bias potential may be applied to one or more of the radio-frequency selector and amplifier 11, oscillator-modulator 14 and the intermediate-frequency amplifier 16, as desired. The variable 55 tuning condensers 12 and 15 are preferably ganged for unicontrol, as indicated by the dotted lines 21. Also ganged with these condensers are the variable tuning condensers 31 and 35, as will be described hereinafter.

60 65 Considering first the operation of the receiver as a whole, and neglecting for a moment the particular characteristics of the coupling system 13, per se, the desired received signal wave is selected and amplified in the radio-frequency selector and amplifier 11, further selected and transferred by the coupling system 13 to the oscillator-modulator 14 where the signal is converted into a modulated intermediate frequency. The signal, as thus converted, is amplified in the intermediate-frequency amplifier 16, rectified by detector 17,

producing the audio frequencies of modulation, which are amplified in the audio-frequency amplifier 18 and reproduced by the sound reproducer 20.

The amplification of the received signal is subject to automatic control by the AVC bias potentials, according to the manner well understood in the art.

The coupling system generally designated 13 comprises two parallel tunable circuits 24 and 25 16 and, between such tunable circuits, two transfer means 26 and 27. The first tunable circuit 24 includes an inductance element 30 and a variable tuning condenser 31, while the second tunable circuit includes an inductance element 34 and a 18 variable tuning condenser 35. Inductance element 34 has the same value as inductance element 30. Variable condensers 31 and 35, and preferably 12 and 15 also, have the same minimum and maximum values, and the same laws of 20 capacitance variation. Tunable circuits 24 and 25 thus have "similar reactance characteristics", which term is used herein to refer to two or more tuned circuits that are electrically similar from the viewpoint of their resonating properties so 25 that normally, in the case of untunable circuits, they are syntonous with each other and, in the case of tunable circuits having conjointly actuated tuning elements, they are in alignment with each other over their respective tuning ranges. 30

The first transfer means 26 includes two series-aligning condensers 32 and 36, of equal value, disposed in relatively low alternating potential portions of the tunable circuits 24 and 25, respectively, and having a common terminal forming a 35 neutral point suitable for grounding, as illustrated. This transfer means includes also an adjustably fixed condenser 38 interconnecting the junction of inductance element 30 and condenser 32 with the junction of inductance element 34 and 40 condenser 36. The condensers 32 and 36 are preferably of relatively large value, at least three or four times the maximum value of the tuning condensers, while the condenser 38 has a value substantially less than that of condensers 32 or 45 36, and generally lying between the minimum and maximum values of the tuning condensers. The condenser 38 is thus effectively external to the tunable circuits 24 and 25 in the sense that the reactance thereof at the operating frequencies is 50 very high relative to the reactance of condensers 32 and 36 so that, for normal adjustments of condenser 32, the resultant variations of reactance of the series combination of condensers 32 and 36, for example, have no appreciable effect 55 on the tuning of the tunable circuit 25.

The second transfer means 27 comprises a condenser connected between the high alternating potential terminals of inductance elements 30 and 34. Condenser 27 has a relatively small 60 value, generally appreciably less than the minimum value of the tuning condensers, and may be adjustably fixed, as indicated. Inductance elements 30 and 34 are inductively unrelated, and thus are conveniently separately mounted, each within an individual grounded shield can, as schematically illustrated. The two tunable circuits 24 and 25 are tuned to the frequency of the desired signal wave conjointly with each other and with the other tunable circuits of the receiver. 65 70

It is to be observed that the two tunable circuits 24 and 25 are symmetrically coupled; that is, the arrangement of the two transfer means is such that each influences the resonant frequencies of both circuits in the same manner and to the 75

same extent. The alignment of the two tunable circuits 24 and 25 is, therefore, not disturbed by adjustments of either of interconnecting condensers 27 or 38. Further, the alignment of tunable circuits 24 and 25 with respect to the other tunable circuits of the system is not disturbed to any substantial extent within the normal limits of the adjustment of condensers 38 and 27.

In considering the transfer action of the coupling system 13, the first transfer means 26 introduces into the second circuit 25 from the circuit 24, across series condenser 36, a voltage which is always a certain definite fraction of the voltage across series condenser 32. The voltage across series condenser 32 varies inversely with the frequency to which the circuits are tuned. The gain or transfer ratio of the first transfer means, therefore, varies inversely with frequency. The fractional relationship of the voltage across condenser 36 to that across condenser 32, that is, the effectiveness of the first transfer means, is subject to control by adjustment of interconnecting condenser 38.

The second transfer means 27 introduces, across the terminals of the second circuit 25, a voltage which varies directly with the frequency to which the first circuit is tuned, for the reactive impedance of interconnecting condenser 27 decreases, and the anti-resonant impedance of the second circuit 25 increases, with increases in the frequency to which the circuits are tuned. The gain or transfer ratio of the second transfer means 25 thus varies directly with frequency. The effectiveness of the second transfer means is subject to control by adjustment of interconnecting condenser 27.

The voltages introduced into the second circuit 25 by the transfer means 26 and 27 are substantially in phase, so that the transfer characteristic of the complete coupling system 13 is substantially the arithmetic sum of their separate transfer characteristics.

The transfer characteristics of the two transfer means 26 and 27 thus vary in opposite senses, with the first transfer means 26 being principally effective at the low-frequency end of the band over which the coupling system is tunable, and with the second transfer means 27 being principally effective at the high-frequency end of such band. As a consequence the over-all transfer characteristic of the complete coupling system 13 may be given any desired slope by suitably adjusting the two transfer means. As previously explained, adjustment of condensers 38 and 27 does not affect the alignment of the two circuits 24 and 25 with respect to each other, or, within the limits of such adjustments, to any substantial extent with respect to the other tunable circuits of the system.

In certain cases, satisfactory control of the over-all transfer characteristic of coupling system 13 may be obtained by adjusting condenser 38 alone. Condenser 27 thus may be furnished as a fixed condenser, which is of commercial advantage since it generally has such a small value. When the desired value of condenser 38 is determined for any particular receiver, condensers 38 for all receivers similar thereto may be fixed condensers of the value ascertained.

Referring now to Fig. 2, the elements therein shown corresponding to similar elements of Fig. 1 are designated by the same reference numerals, or, if of modified form, with the addition of a prime or a lettered suffix. Included among such elements are the antenna circuit 10, the radio-frequency selector and amplifier 11', the va-

riably tuned, double-tuned coupling system 13', the oscillator-modulator 14', the intermediate-frequency amplifier 16, the detector and automatic amplification control source 17, the audio-frequency amplifier 18, the sound reproducer 20, 5 the variable tuning condensers 12, 31, 35 and 15 and their unicontrol mechanism represented by the dotted lines 21, the tunable circuits 24' and 25', the first transfer means 26' including the fixed condensers 32 and 36, and the second 10 transfer means 27'. Inasmuch as the receiver of Fig. 2 is of the multi-band type, band-selecting switching mechanisms 40 and 41 are provided for the selector and amplifier 11' and for the oscillator-modulator 14', respectively. These switches 15 selectively connect a plurality of inductance coils (not shown) in circuit with their respective tuning condensers. Switches 40 and 41 are preferably ganged for unicontrol, as indicated by the dotted lines 42, with which are also ganged the switches 20 43, 44 and 45, as will be described hereinafter.

Each of the two tunable circuits 24' and 25' of coupling system 13' is selectively tunable over the several frequency bands over which the selector and amplifier 11' is tunable. This band 25 selection is effected by switches 43 and 44, which selectively connect in circuit with the tuning condensers 31 and 35, respectively, the inductance elements 30a and 34a, 30b and 34b, 30c and 34c, and 30d and 34d, for the several frequency bands a, b, c, and d, respectively, which, in the order given, are progressively higher in the frequency spectrum. Each inductance element may be effectively shunted by a small adjustably fixed trimmer condenser, as illustrated. 35

The first transfer means 26' of coupling system 13' comprises the series condensers 32 and 36, and the interconnecting condensers 38a, 38b, 38c and 38d, which are selectively connected into the coupling system by the switch 45 for the 40 several bands a, b, c, and d, respectively.

The second transfer means 27' of coupling system 13' comprises the condensers 21a, 21b, 27c and 27d interconnecting the high potential ends of the inductance elements 30 and 34 for the 45 several bands a, b, c, and d, respectively. Preferably, the several inductance elements 30 are wound on one form and the several inductance elements 34 are wound on another form, with each form and its windings mounted within a 50 separate grounded shield can, as illustrated.

The receiver of Fig. 2, including the coupling system 13', operates in each band in the same manner as that described for the single band receiver of Fig. 1, so further discussion of such 55 operation is believed unnecessary. From band to band, however, the effectiveness of the coupling system 13' varies, this variation being attained by altering the effectiveness of each transfer means as the switches are shifted for reception in the several bands. Inasmuch as the present types of multi-band receivers have an attainable over-all gain which becomes appreciably smaller as the bands are higher in the frequency spectrum, and inasmuch as it is generally desirable to have an over-all gain which is more nearly uniform from band to band, it is preferred to arrange the coupling system 13' so that it compensates for part, if not all, of such 60 band-to-band variation in the over-all gain. This is conveniently accomplished by increasing the effectiveness of each of the transfer means 26' and 27' as the bands over which the receiver is 65 adjusted to operate are higher in the frequency 70 75

spectrum. As a result, the capacitances of the interconnecting condensers 38a, 38b, 38c and 38d for the first transfer means 26' and of the interconnecting condensers 27a, 27b, 27c and 27d for the second transfer means 27', increase in magnitude in the order named.

Fig. 3 illustrates a multi-band coupling system 113 which may be used in lieu of the multi-band coupling system 13' of Fig. 2. For convenience, the elements illustrated in Fig. 3 corresponding to similar elements illustrated in Fig. 2 are designated by the same reference numerals, except that numbers in the 100 series are employed. The coupling system 113 is a double-tuned system for each of the bands *a*, *b* and *c*, but is a single-tuned system for the highest frequency band *d*. The attendant sacrifice of selectivity in band *d* is desirable in certain cases in order to obtain in such band as high a transfer ratio as possible.

For each of the bands *a*, *b*, and *c*, the coupling system 113 is electrically equivalent to that shown in Fig. 2. For simplicity, however, no separate condenser is provided as the interconnecting condenser of the second transfer means 127 in band *a*, recourse being had to the small inherent capacitance, represented in dotted lines as the capacitance 155, between the two tunable circuits 124 and 125, this capacitance existing primarily between the leads to the switches 143 and 144. The interconnecting condenser of the second transfer means 127 is, in band *b*, a turn 156 of an insulated wire 157 about the lead to the high potential terminal of inductance element 130b and a turn 158 of the same insulated wire about the lead to the high potential terminal of inductance element 134b, while, in band *c*, it is a turn 160 of an insulated wire 161 about the lead to the high potential terminal of inductance element 134c, the other end of wire 161 being connected to the high potential terminal of inductance element 130c. Also, for simplicity, no separate interconnecting condenser for the first transfer means 126 is provided for bands *b* and *c*, the condenser 138c being made to serve for both bands *b* and *c*.

To minimize any influence upon the coupling system of spurious resonances in any unused inductance element, switches 151 and 152 are arranged to short-circuit the several inductance elements 130 and 134, respectively, for those bands below that to which the receiver is tuned. To avoid tuning directly, as in Fig. 2, the plate circuit of the preceding amplifier tube of the system, the tunable circuit 124 is coupled, for each of bands *a*, *b*, and *c*, inductively and capacitively to the untuned primary windings 153a, 153b and 153c by means of inductance elements 130a, 130b and 130c, respectively, the windings 153a, 153b and 153c being selectively connected to the plate circuit of the preceding tube by the switch 150. The primary windings are preferably so poled that the inherent capacitive coupling between the respective primary windings and their corresponding inductance elements operates, for bands *a* and *b*, and aids, for band *c*, the inductive coupling therebetween.

For band *d*, in which the coupling system 113 operates as a single tuned system, the second tunable circuit 125 for such band is coupled inductively and capacitively to the input of the system by the primary winding 153d which, as with the other primary windings 153, is controlled by the switch 150.

In view of the preceding descriptions relative

to Figs. 1 and 2, it is believed that no further description of Fig. 3 is necessary.

It is to be understood that the invention is not limited to any particular frequency range or set of ranges. In order, however, to illustrate the relative magnitudes of the principal elements of coupling systems designed in accordance with this invention, the following approximate values of such elements, together with other pertinent information, are given for a particular receiver of the type shown in Fig. 2.

Frequency range

Band <i>a</i> , kilocycles	530-1525
Band <i>b</i> , megacycles	1.44-4.05 15
Band <i>c</i> , megacycles	4.0-10.0
Band <i>d</i> , megacycles	9.0-21.0

Inductance elements 30a and 34a—139½ turns—No. 32E close wound.

Inductance elements 30b and 34b—34½ turns—No. 32E—88 turns per inch.

Inductance elements 30c and 34c—11½ turns—No. 24E—36 turns per inch.

Inductance elements 30d and 34d—4½ turns—No. 18E—16 turns per inch.

All coils wound on 1" diameter forms.

While I have described what I at present consider the preferred embodiments of my invention, it will be obvious to those skilled in the art that various changes and modifications may be made therein without departing from my invention, and I, therefore, aim in the appended claims to cover all such changes and modifications as fall within the true spirit and scope of my invention.

What is claimed is:

1. A coupling system operative over a band of frequencies comprising; a pair of tuned circuits having substantially similar reactance characteristics; and means for coupling said circuits to

obtain a transfer characteristic over said band which is readily subject to control without disturbing the syntony of said circuits including a self-reactance network all the reactances of 5 which are of the same type and normally fixed in value, said network having two similar arms of equal effective reactive value individually and symmetrically included in circuit with said tuned circuits and having another arm symmetrically interconnecting said two similar arms, control of the transfer action of said system being effected by altering the effective reactive 10 value of said interconnecting arm.

2. A coupling system operative over a band of 15 frequencies including: two tuned circuits having substantially similar reactance characteristics; and means for coupling said circuits, said means having a transfer characteristic variable with frequency and comprising fixed reactance 20 elements of the same type and of substantially equal value individually and symmetrically connected in circuit with said tuned circuits, and normally fixed reactance means effectively external to said circuits, and also of said type, 25 coupling said individual reactance elements.

3. A coupling system operative over a band of frequencies including: two tuned circuits having substantially similar reactance characteristics; and means for coupling said circuits, said 30 means having a transfer characteristic variable with frequency and comprising a plurality of fixed reactance elements of the same type including at least one pair, the elements of each pair having substantially equal values and being individually and symmetrically connected in circuit with said tuned circuits, with at least one of said individual reactance elements of a first of said tuned circuits together with at least one other reactance element effectively external 35 to said circuits forming a voltage dividing arrangement across the corresponding individual reactance element of the other of said tuned circuits.

4. A coupling system operative over a band of 40 frequencies including: a pair of tuned circuits having similar reactance characteristics; and means for coupling said circuits, said means having a transfer characteristic variable with frequency and comprising fixed self-reactance 45 elements of the same type and of substantially the same value individually and symmetrically connected in circuit with said tuned circuits, and an additional self-reactance element of said type connected effectively external to said circuits, said additional self-reactance element being adjustably fixed and similarly associated with each of said circuits so that adjustment of said one additional element, exclusively, varies the 50 transfer action of said coupling means without disturbing the syntony of said circuits.

5. A coupling system operative over a band of 55 frequencies including: two tuned circuits having substantially similar reactance characteristics; and means for coupling said circuits, said means having a transfer characteristic variable with frequency and comprising at least one pair of fixed reactance elements of the same type, the reactance elements of each pair having substantially equal values and being individually and symmetrically connected in circuit with said tuned circuits with at least one pair of said reactance elements having a common terminal, and at least one additional fixed reactance 60 element of the same type as said first reactance ele-

ments effectively external to said circuits, coupling corresponding points of a pair of said first reactance elements.

6. A coupling system operative over a band of frequencies including: two tuned circuits having substantially similar reactance characteristics; and means for coupling said circuits, said means having a transfer characteristic variable with frequency and comprising three fixed self-reactance elements of the same type, two thereof being of substantially equal value and symmetrically and individually connected in circuit with said tuned circuits and the third thereof being effectively external to said circuits and having a reactance substantially greater than, and interconnecting corresponding points of, said first two reactance elements.

7. A coupling system operative over a band of frequencies including: two tuned circuits having substantially similar reactance characteristics; and means for coupling said circuits, said means having a transfer characteristic variable with frequency and comprising three fixed reactance elements of the same type, two thereof being of substantially equal value and symmetrically and 25 individually connected in portions of relatively low alternating potential of said circuits and having a common terminal, and the third thereof being effectively external to said circuits and interconnecting the other terminals of said first 30 two reactance elements.

8. A coupling system tunable over a band of frequencies comprising; a pair of tuned circuits having substantially similar reactance characteristics; and means for coupling said circuits to 35 obtain a transfer characteristic over said band which is readily subject to control without disturbing the syntony of said circuits including a capacitance network all the condensers of which are normally fixed, said network having two similar arms of equal effective capacitance individually and symmetrically included in circuit with said tuned circuits and having another arm effectively external to said circuits and symmetrically interconnecting said two similar arms, control of 40 the transfer action of said system being effected by altering the effective capacitance of said interconnecting arm.

9. A coupling system operative over a band of 45 frequencies including: two tuned circuits having substantially similar reactance characteristics; and means for coupling said circuits, said means having a transfer characteristic variable with frequency and comprising three normally fixed condensers, two thereof being of substantially 50 equal value and symmetrically and individually connected in circuit with said tuned circuits and the third thereof effectively external to said circuits and interconnecting corresponding terminals of said first two condensers.

10. A coupling system operative over a band of 55 frequencies including: two tuned circuits having substantially similar reactance characteristics; and two transfer means between said tuned circuits having transfer characteristics which vary 60 with frequency in opposite senses, one of said transfer means comprising fixed reactance elements of the same type and of substantially equal value individually and symmetrically connected in circuit with said tuned circuits, and fixed 65 reactance means effectively external to said circuits, and also of said type, coupling said individual reactance elements.

11. A coupling system operative over a band of 70 frequencies including: a pair of inductively un- 75

related tuned circuits having substantially similar reactance characteristics; and two transfer means for coupling said circuits to obtain a desired transfer characteristic over said band, a 5 first transfer means comprising self-reactance means coupling portions of said circuits of relatively high alternating potential and a second transfer means including self-reactance means effectively external to both of said circuits coupling portions thereof of relatively low alternating potential, said two transfer means having transfer characteristics which vary oppositely with frequency.

12. A coupling system operative over a band of 15 frequencies including: a pair of inductively unrelated tuned circuits having substantially similar reactance characteristics; and two transfer means for coupling said circuits to obtain a desired transfer characteristic over said band, a 20 first transfer means comprising fixed self-reactance means coupling portions of said circuits of relatively high alternating potential and a second transfer means comprising fixed self-reactance means of the same type as said first self-reactance means, at least a portion of which is effectively external to both of said circuits, coupling portions of said circuits of relatively low alternating potential, said two transfer means having transfer characteristics which vary oppositely with frequency.

13. A coupling system operative over a band of 30 frequencies including: two tuned circuits having substantially similar reactance characteristics; means for coupling said circuits to obtain a desired transfer action over said band comprising a first transfer means coupling portions of said circuits of relatively low alternating potential and a second transfer means coupling portions of said circuits of relatively high alternating potential, each of said transfer means having a transfer characteristic variable with frequency and one of said transfer means comprising a plurality of fixed reactance elements of the same type and of substantially equal value individually and 40 symmetrically connected in circuit with said tuned circuits, and additional fixed reactance means, also of said type, coupling said individual reactance elements.

14. A coupling system operative over a band of 50 frequencies including: two tuned circuits having substantially similar reactance characteristics; and means for coupling said circuits comprising two transfer means between said circuits having transfer characteristics which vary in opposite 55 senses with frequency, the transfer means having the transfer characteristic which rises with frequency coupling portions of said circuits of relatively high alternating potential and the transfer means having the transfer characteristic 60 which falls with frequency coupling portions of said circuits of relatively low alternating potential, the latter transfer means comprising fixed reactance elements of the same type and of substantially equal value symmetrically and individually connected in circuit with said tuned circuits, and normally fixed reactance means, also of said type, coupling said individual reactance elements.

15. A coupling system operative over a band of 70 frequencies including: two inductively unrelated tuned circuits having substantially similar reactance characteristics; and means for coupling said circuits comprising two transfer means between 75 said circuits having transfer characteristics

which vary in opposite senses with frequency, the transfer means having the transfer characteristic which rises with frequency comprising a relatively small fixed condenser coupling portions of said circuits of relatively high alternating potential, and the transfer means having the transfer characteristic which decreases with frequency comprising two relatively large fixed condensers of substantially equal value symmetrically and individually connected in series in portions of 10 said circuits of relatively low alternating potential and having a common terminal, and a normally fixed condenser of predetermined value less than said two large fixed condensers interconnecting the other terminals thereof.

16. A coupling system tunable over a band of 15 frequencies including: two tunable circuits having substantially similar reactance characteristics and conjointly operated tuning elements; and means for coupling said circuits, said means having a transfer characteristic variable with the frequency to which said circuits are tuned and comprising fixed reactance elements of the same type and of substantially equal value individually and symmetrically connected in circuit with said tunable circuits, and fixed reactance means, also of said type, coupling said individual reactance elements.

17. A coupling system tunable over a band of 30 frequencies including: a pair of tunable circuits having substantially similar reactance characteristics and conjointly operated tuning elements; and two transfer means for coupling said circuits to obtain a desired transfer characteristic over said band, a first transfer means comprising fixed self-reactance means coupling portions of said circuits of relatively high alternating potential and a second transfer means including fixed self-reactance means external to both of said circuits coupling portions thereof of relatively low-alternating potential, said two transfer means having transfer characteristics which vary oppositely with the frequency to which said circuits are tuned.

18. In a superheterodyne receiver for operation over a band of frequencies and having an oscillator tunable by a tuning means: a radio-frequency coupling system tunable with said oscillator comprising: two tunable circuits having substantially similar reactance characteristics, 50 each of which circuits includes a variable tuning means, both said variable tuning means being similar to, and actuated conjointly with, the tuning means of said oscillator; and means for coupling said circuits so that the alignment thereof with respect to each other and with respect to said oscillator is substantially unaffected by adjustment of the coupling of said coupling means and for controlling the frequency transfer characteristic of said coupling means, said means comprising a self-reactance network all the reactances of which are of the same type and normally fixed in value, said network having two similar arms of equal effective reactive value individually and symmetrically included in circuit with said tuned circuits and having another arm symmetrically interconnecting said two similar arms, control of the transfer action of said system being effected by altering the effective reactive value of said interconnecting arm.

19. In a superheterodyne receiver for operation over a band of frequencies and having an oscillator tunable by a tuning means: a radio-frequency coupling system tunable with said oscillator comprising: two tunable circuits having 75

- substantially similar reactance characteristics, each of which circuits includes a variable tuning means, and fixed self-reactance series aligning means, both said variable tuning means being similar to, and actuated conjointly with, the tuning means of said oscillator; and means for coupling said circuits so that the alignment thereof with respect to each other and with respect to said oscillator is substantially unaffected by adjustment of the coupling of said coupling means and for controlling the frequency transfer characteristic of said coupling means, said means comprising said two aligning means and a reactance means of the same type as said two series aligning means and coupling corresponding electrically spaced points thereof.
20. In a superheterodyne receiver for operation over a band of frequencies and having an oscillator tunable by a tuning element thereof: a radio-frequency coupling system tunable with said oscillator comprising; two tunable circuits having substantially similar reactance characteristics, each of said circuits including a variable tuning element similar to and actuated conjointly with said oscillator tuning element; and means for coupling said circuits so that the alignment of said circuits with respect to each other and with respect to said oscillator is substantially unaffected by adjustment of the coupling of said means, consisting of two transfer means having transfer characteristics which vary in opposite senses with the frequency to which said circuits are tuned, said transfer means respectively coupling portions of said circuits of relatively low and relatively high alternating potential, and one of said transfer means including effectively fixed reactance elements of the same type and of substantially equal value individually and symmetrically included in circuit with said tunable circuits, and effectively connecting corresponding electrically spaced points of said reactance elements.
21. A coupling system operative over two or more bands of frequencies including: a pair of tuned circuits for each of said bands, the two circuits of each of said pairs having similar reactance characteristics; means for selectively connecting the two circuits of each of said pairs in circuit with the input and output of said coupling system, respectively; and means for coupling the two circuits of each of said pairs of circuits, said last-named means having for each of said bands a transfer characteristic variable with frequency and comprising for each of said bands fixed reactance elements of the same type and of substantially equal value individually and symmetrically connected in circuit with the corresponding tuned circuits, and a normally fixed reactance means, also of said type, coupling said individual reactance elements.
22. A coupling system operative over two or more bands of frequencies including: a pair of tuned circuits for each of said bands, the two circuits of each of said pairs having similar reactance characteristics; means for selectively connecting the two circuits of each of said pairs in circuit with the input and output of said coupling system, respectively; and means for coupling the two circuits of each of said pairs of circuits, said last-named means having for each of said bands a transfer characteristic variable with frequency and comprising for all of said bands fixed reactance elements of the same type and of substantially equal value individually and
- symmetrically connected in circuit with all the corresponding tuned circuits, a plurality of normally fixed reactance means of said type, one for each of said bands, having different reactive values, and means for selectively connecting said normally fixed reactance means in circuit to couple said individual reactance elements.
23. A coupling system operative over two or more bands of frequencies including: a pair of tuned circuits for each of said bands, the two circuits of each of said pairs having similar reactance characteristics; means for selectively connecting the two circuits of each of said pairs in circuit with the input and the output of said coupling system, respectively; and two transfer means between the two circuits of each of said pairs, said two transfer means having transfer characteristics which vary in opposite senses with frequency, the transfer means for the several pairs being proportioned to have a resultant transfer ratio which increases from pair to pair as the bands of frequencies to which the pairs are tuned are higher in the frequency spectrum.
24. A coupling system tunable over two or more bands of frequencies including: a pair of tunable circuits for each of said bands, the two circuits of each of said pairs having similar reactance characteristics and conjointly operated tuning elements; means for selectively connecting the two circuits of each of said pairs in circuit with the input and output of said coupling system, respectively; and means for coupling the two circuits of each of said pairs of circuits, said last-named means having for each of said bands a transfer characteristic variable with the frequency to which said circuits are tuned and comprising for each of said bands fixed reactance elements of the same type and of substantially equal value individually and symmetrically connected in circuit with the corresponding tunable circuits and a normally fixed reactance means, also of said type, coupling said individual reactance elements.
25. A coupling system tunable over two or more bands of frequencies including: a pair of tunable circuits for each of said bands, the two circuits of each of said pairs having substantially similar reactance characteristics, a single tuning element for each group of corresponding circuits of said pairs, and means for selectively connecting said tuning elements in circuit with the respective fixed reactance elements individual to the several pairs and for selectively connecting the two circuits of each pair with the input and the output of said coupling system, respectively; and means for coupling the two circuits of each of said pairs to obtain a substantially uniform transfer ratio over each of the tunable ranges of the several pairs and a transfer ratio which increases, from band to band, as the bands are higher in the frequency spectrum, comprising two transfer means between the two circuits of each of said pairs of circuits, said two transfer means for each pair having transfer characteristics which vary in opposite senses with variation in the frequency to which the associated pair of circuits are tuned, and coupling, respectively, the low and high potential portions of the associated circuits.
26. A coupling system tunable over two or more bands of frequencies including: a pair of tunable circuits for each of said bands, the two circuits of each of said pairs having substantially similar reactance characteristics, and including fixed inductance elements individual to the sev-

- eral circuits and a common connection for the low potential ends of the inductance elements of each of the two groups of corresponding circuits of said pairs, said circuits including a variable 5 tuning condenser for each of said groups, and means for selectively connecting said tuning condensers in circuit with the respective fixed inductance elements individual to the several pairs and for selectively connecting the two circuits of each 10 pair with the input and the output of said coupling system, respectively; and means for coupling the two circuits of each of said pairs to obtain a substantially uniform transfer ratio over each of the tunable ranges of the several pairs 15 and a transfer ratio which increases from band to band as the bands are higher in the frequency spectrum, comprising; a first transfer means between the two circuits of each of said pairs of

circuits having a transfer characteristic which varies inversely with frequency and comprising relatively large fixed condensers of substantially the same value connected respectively between said common low potential ends of each of said groups of circuits and ground, a plurality of normally fixed condensers, and means for selectively connecting said normally fixed condensers between said common low potential ends; and a second transfer means between the two circuits 10 of each of said pairs of circuits having a transfer characteristic which varies directly with frequency and comprising relatively small normally fixed condensers connected between the high potential ends of the inductance elements for each 15 of said pairs of circuits.

NELSON P. CASE.
